UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

MAGNETO.

Application filed July 2, 1921. Serial No. 482,053.

To all whom it may concern:

Be it known that I, EDWARD B. NOWOSIELSKI, a citizen of the United States, residing at Bloomfield, in the county of Essex, State of New Jersey, have invented certain new and useful Improvements in Magnetos, of which the following is a description, reference being had to the accompanying drawing and to the figures of reference marked 10 thereon.

This invention relates to magnetos and in particular to the circuit breaker mechanism and high tension distributor mechanism thereof.

15 It is an object of this invention to enclose these mechanisms within a unitary housing, such that when the cover is removed, all of the breaker and distributor mechanisms are exposed for inspection and repair.

20 It is a further object of this invention to so construct the above mechanisms that the whole may be removed for replacement and repair without dismantling the current generating portion of the magneto.

25 These and further objects will be apparent after reading the following specification and claims in connection with the accompanying drawings in which—

Figure 1 is a sectional view of my complete magneto.

Figure 2 is an interior view of my housing front plate showing the circuit breaker and high tension distributor mechanism in place.

35 Figure 3 is an interior view of the cover for my housing front plate.

Figure 4 is a view similar to Fig. 2, some of the parts being removed.

40 Figure 5 is a diagrammatic cross sectional view of the magneto showing the relationship between the pole pieces, the magnet and the induction coil.

Figure 6 is a detailed view on a reduced scale illustrating the mechanism for driving the distributor spool.

Figure 7 is a fragmentary view of a portion of my mechanism, also on a reduced scale, and

Figure 8 is a back view of the condenser employed with my construction.

Now referring to the several figures more in detail, 1 indicates a base structure to which is secured an end plate 2 and a housing 3 as by means of screws 4. The end plate 2 and housing 3 carry bearings for a

rotor 5, and are, therefore, generally referred to as the back and front plates, respectively, of the magneto, said rotor being of the inductor type and acting to direct the flux from a permanent magnet 6 in alternately 60 opposite directions through the core 7 of an induction coil 8 via magnet pole pieces 80 and 81 and core pole pieces 9 and 10 embedded in the base structure 1. The induction coil is provided with a high tension 65 terminal 11 which projects within a bore 12 of a connector block 13 and makes contact with a metallic insert 14 therein through a coiled spring 15. The connector block is seated within an opening in the back wall 70 of the housing 3, and is provided with a shoulder 16 to fit against the edge of the opening. To retain the same against displacement a metallic ring 17 is provided, 75 said ring having two ears 18 secured to the back wall of the housing by means of screws 19. Since the ring is grounded to the housing, it is spaced away from the connector block adjacent to the exposed portion 20 of the insert 14 to provide a suitable air gap 80 therewith, and an annular flange 21 is provided to bear against a shoulder 22 on the connector block to retain the same in place. Mounted within the housing is a spider, its legs 23 being secured to the back wall of 85 the housing by means of a stud 24 and screws 25. Rigidly secured in the hub of the spider is a bearing 26 within which is rotatably carried a hollow shaft 27 having fixed to it a gear 28 meshing with a second 90 gear 29 keyed on to a projecting shaft end 30 of the rotor 5. The shaft 27 is held against lateral displacement through the expedient of a snap ring 31 engaging a circumferential groove 84 in the shaft. Slidably retained within the hollow shaft is the 95 shaft of a distributor spool 32, the same having a metallic core 33 bored out at its end to receive a spring pressed brush 34 preferably of carbon to collect the current from 100 the insert 14 in the connector block 13. The core adjacent the bored out end is provided with a ring 35 which cooperates with the grounded metallic ring 17 to form a safety 105 spark gap therewith so as to prevent rupture of the coil should the secondary circuit remain open during operation of the magneto. The spool is driven by the hollow shaft through a key 36 moulded on the distributor spool engaging within a slot 37 in the 110

shaft 27. To lubricate the bearing, a cup 38 is frictionally retained on a flanged portion of the bearing within which may be packed some semi-solid lubricant and a 5 spring pressed wick 39 may feed the lubricant to the bearing surface of the shaft 27 through an opening 40 in the bearing 26. The spool 32 is retained against lateral displacement by means of a spring pressed 10 thrust button 41 secured in a distributor block 42 held to the cover 43 of the housing 3 by means of a rod 44 which extends from side to side of the cover and which is secured at its ends by means of pins 45 15 secured in ears 46 moulded on the cover 43. The distributor block is provided with collector brushes 47 which are connected to the high tension leads of the magneto by means of stiletto cable connections 48, only one 20 of which is shown in Fig. 1, the path of the high tension current then being from the coil through the brush 11, insert 14 in the connector block, the brush 34, core 33, an insert 49 in the distributor spool, one of 25 the collector brushes 47, and from a cable connection 48 to the engine spark plug and ground back to a grounded end of the induction coil.

One end of the primary circuit of the 30 induction coil is connected by a cable 50 which may be enclosed by a sheath 51 throughout a portion of its length, with a stationary contact 52 as by means of a screw 53, said contact being mounted on an ear 35 struck up from a plate 54 secured to a breaker base plate 55 by means of screws 56 and insulated therefrom by an insulating plate 57. Also struck up from the same plate is a wiper holder having prongs 58 40 between which is pinched a felt wiper 59 bearing on the elevated portions of a cam 60 removably secured on the shaft 30, to wipe off any excess oil that may have collected thereon. The breaker base plate is 45 essentially annular in form and is free to rotate in bosses 61 cast up from the back wall of the housing, said bosses being suitably shouldered as at 62 to rotatably seat the breaker base plate. To retain the same 50 against lateral displacement two spring clips 63 are provided, the same being secured to the housing 3 by means of studs 64 tapped into holes 65 in the housing. The studs 24 and 64 are each threaded at their free ends 55 and project through apertures 66 in the cover 43, nuts 67 being provided to secure the cover to the housing, and a suitable cork or felt gasket 68 being interposed at the joint to render the housing moisture and 60 dust proof. Mounted on a stud on the breaker base is a lever arm 69 carrying at one end a contact 70 and at its other end a bumper 71, and a spring 72 is secured to said lever arm and its free end rests against 65 a projecting arm 73 struck up from the base

to resiliently maintain the contacts 52 and 70 in engagement. The cam 60 in its rotation engages the bumper to make and break the primary circuit through the contacts 52 and 70, the lever arm 69 being grounded 70 directly to the frame by means of a cable 74 secured beneath one of the studs 64. Bridging the contacts 52 and 70 is a condenser 75, the terminals of which are secured to the screw 53 and to a stud 76 which 75 is tapped into the breaker base.

The back of the condenser has a struck up portion 85 to which is rigidly secured a leaf spring 86 as by a nut 87, said spring being provided at its free end with a button 88 adapted to bear against the hub of the lever arm, to retain the same on the stud when the condenser is in position.

In order to oscillate the breaker base plate carrying the breaker mechanism to advance or retard the spark, as will be well understood by those skilled in the art, a bell crank lever 77 is journaled in the cover 43 and the same may be actuated by means of a rod or a cable engaging an exterior end portion 78 thereof. The inner end of the bell crank has a portion engaging a slotted portion 79 of the breaker base plate. The spider is provided with a projection 82 adapted to engage an arc shaped recess 83 in the breaker base plate to limit the extreme advanced and retarded positions thereof.

From the above description it will be seen that by removing the nuts 67 that the cover 43 of the housing may be removed together with the distributor block 42, thereby exposing the circuit breaker and high tension distributor mechanism. The above mechanisms may then be dismembered for repair or replacement as follows.

The distributor spool 32 may be simply slid out of its hollow shaft; the stud 24 and screws 25 being removed, the spider together with the gear 28, bearing 26 and its lubricating mechanism may be removed and thereafter these latter parts may be disassociated by removing the snap ring 31 and by prying off the cover 27 from the bearing 26. If so desired, the high tension connector block and safety spark gap may be removed by removing the two screws 19.

The condenser 75 may be easily removed by removing the screws 53 and 76. The lever arm 69 with its contact and spring may be removed from off its stud without loosening any screws, etc., the end of the spring 72 being free and not screwed down to a fixed portion of the breaker base plate as is now the common construction, and the breaker base plate with its entire mechanism may be lifted off from its boss by removing the spring clips 63.

I have thus provided a magneto wherein all of the parts are enclosed within a single housing in such a manner that all of the

parts may be exposed for inspection, repair or replacement, without disturbing the current generating portion of the magneto.

Having thus described my invention what

5 I claim is:

1. In a magneto, a front plate forming a substantial part of a housing, a metallic cover for said housing, a rotary distributor finger and distributor mechanism enclosed

10 within said housing, a distributor block detachably carried by and removable with said cover and having parts extending through the cover into cooperative engagement with said rotary distributor; all the portions of

15 said mechanism being readily removable from the housing upon removal of the cover.

2. In a magneto, a front plate forming a housing, a removable metallic cover therefor carrying a quickly detachable distributor 20 block, a distributor spool co-operating therewith, a hollow shaft slidably retaining the spool and driving the same, a gear secured to the hollow shaft, a bearing detachable from the interior of the housing provided

25 with means for retaining said gear and shaft in place within the housing and means cooperating with the gear to drive the same.

3. In a magneto having an induction coil, 30 a front plate forming a housing, a removable cover therefor carrying a distributor block, a distributor spool cooperating therewith, a hollow shaft slidably retaining the spool and driving the same, a gear secured to the hollow shaft, a bearing detachable from the interior of the housing provided

35 with means for retaining said gear and shaft in place within the housing, and a connector block for completing a circuit between said

40 induction coil and the distributor spool secured in said housing and removable from the interior thereof.

4. In a magneto, a housing, a removable cover therefor carrying a distributor block,

45 a distributor spool provided with a conductive element cooperating therewith, a hollow shaft slidably retaining the spool and driving the same, a gear secured to the hollow shaft, a bearing detachable from the interior of the housing provided with means

50 for retaining said gear and shaft in place within the housing, a connector block having a grounded metallic ring spaced from the distributor spool conductive element and

55 forming a safety spark gap therewith secured in said housing and removable from the interior thereof and means cooperating with the gear to drive the same.

5. In a magneto, a housing, a removable cover therefor carrying a distributor block,

60 a distributor spool provided with a conductive element cooperating therewith, a hollow shaft slidably retaining the spool and driving the same, a gear secured to the hollow

65 shaft, a bearing detachable from the in-

terior of the housing provided with means for retaining said gear and shaft in place within the housing, a connector block having a grounded metallic ring spaced from the distributor spool conductive element and forming a safety spark gap therewith secured in said housing and removable from the interior thereof, said connector block being provided with a flange to rest against the interior of the housing and said ring having ears to receive screws to bind the same and the connector block to the housing.

6. In a magneto, a distributor mechanism comprising a hollow shaft, a distributor spool having a portion in said hollow shaft, said shaft being rotatably mounted in a bearing, and lubricating mechanism for said shaft comprising a cup frictionally retained on and encompassed about the bearing, an opening through said bearing from said cup to the shaft and a lubricating wick in said opening.

7. In a magneto, a housing, a cover therefor, and readily dismemberable distributor mechanism comprising a hollow shaft, a distributor spool slidably removable therefrom but rotatable therewith, said shaft being rotatably mounted in a bearing, a snap ring retaining the shaft from removal from said bearing, and lubricating mechanism for said shaft comprising a cup frictionally retained on and encompassed about the bearing, an opening through said bearing from said cup to the shaft and a lubricating wick in said opening.

8. In a magneto, a housing, a cover therefor, and readily dismemberable distributor mechanism comprising a hollow shaft, a distributor spool slidably removable therefrom but rotatable therewith, said shaft being rotatably mounted in a bearing, a snap ring retaining the shaft from removal from said bearing, and lubricating mechanism for said shaft comprising a cup frictionally retained on and encompassed about the bearing, an opening through said bearing from said cup to the shaft and a lubricating wick in said opening; said spool, shaft, lubricating cup and gear being removable as a unit from 115 said housing.

9. In a magneto, a housing, a rotor having a shaft end projecting into said housing, a removable cam on said shaft end, a boss in said housing, a breaker base rotatably mounted on said boss, a spring clip removably secured in said housing and retaining said breaker base in place on said boss, and a circuit breaker mounted on said base cooperating with the cam.

10. In a magneto, a housing, a circuit breaker mechanism housed therein comprising a breaker base, a lever mounted thereon, a bumper and a contact at opposite ends of said lever, a cam cooperating with said

bumper, and an insulated plate mounted on said breaker base, said plate being bent to provide a holder for a wiper, a wiper in said holder cooperating with the cam, said plate being further bent to provide a stationary mounted contact in position to cooperate with the lever carried contact, and means to connect said plate to a conductor.

11. In a magneto, a front plate forming a housing, a distributor mechanism mounted in the upper part of said housing; a circuit breaker mechanism housed within the lower portion of said housing comprising a breaker base plate, a contact carrying lever mounted thereon, a stationary contact mounted on said breaker base plate in position to cooperate with said lever carried contact, and a spring member secured to the lever urging said contacts into engagement, the other end of said spring bearing against an abutment on said plate but being free and unattached therefrom.

12. In a magneto, a housing, a circuit breaker mechanism housed therein comprising a breaker base plate, a contact carrying lever mounted thereon, a stationary contact mounted on said breaker base plate in position to cooperate with said lever carried contact, and a condenser fixed in position above the contact lever, said condenser having a resilient arm bearing on the contact carrying lever to maintain the same on its pivot.

13. In a magneto, a front plate forming a housing, a spider mounted within the top portion of said housing and carrying a distributor mechanism including a bearing shaft, gear and distributor spool with lubricating mechanism for the shaft and bearing, a circuit breaker mechanism carried in the

lower portion of said housing, comprising a breaker base plate carrying a stationary and movable contact, and a single cover plate for closing said housing.

14. In a magneto a front plate forming a housing, a spider mounted within the top portion of said housing and carrying a distributor mechanism including a bearing shaft, gear and distributor spool with lubricating mechanism for the shaft and bearing, a circuit breaker mechanism carried in the lower portion of said housing, comprising a breaker base plate carrying a stationary and movable contact, a single cover plate for enclosing said housing, and a distributor block carried on the cover plate and cooperating with the distributor mechanism within the housing, and a control lever having a bearing on the cover plate with a part extending into engagement with said breaker base plate.

15. In a magneto, a front plate forming a housing, a spider mounted within the top portion of said housing and carrying a distributor mechanism including a bearing shaft, gear and distributor spool with lubricating mechanism for the shaft and bearing, a circuit breaker mechanism mounted within the lower portion of said housing comprising a breaker base plate carrying a movable contact and a cooperating adjustable contact together with a condenser bridged across said contacts, a single cover plate carrying a distributor block and cooperating with said distributor mechanism and a lever for adjustably moving said breaker mechanism.

In testimony whereof I affix my signature.

EDWARD B. NOWOSIELSKI.
